UNITED STATES PATENT OFFICE.

GEORGE A. LOGAN, OF BOSTON, MASSACHUSETTS.

COIN-MAILING CARD.

1,003,478.

Specification of Letters Patent. Patented Sept. 19, 1911.

Application filed January 4, 1911. Serial No. 600,691.

To all whom it may concern:

Be it known that I, GEORGE A. LOGAN, residing at Boston, in the county of Suffolk and State of Massachusetts, have invented 5 an Improvement in Coin-Mailing Cards, of which the following is a specification.

This invention relates to coin-cards or holders, especially designed for mailing purposes, and has for its object to construct 10 a card having one or more coin-receiving spaces, each space being normally filled with a partially severed piece of the card itself, which may be torn out or otherwise removed whenever desired to place a coin in the 15 space, said spaces being other than round, as for instance square, and to arrange the integral connecting portions which are provided between the filling piece and the card itself at the corners, so that in case a filling 20 piece is removed by tearing, the multilated edges produced by the tearing operation will not obstruct the space in such manner as to prevent the easy entrance of a coin.

Figure 1 is a perspective view of a coin-mailing card embodying this invention. Fig. 2 is a front view of the coin-mailing card, the holder being detached. Fig. 3 is a vertical section on the dotted lines 3—3. Fig. 4 is a portion of the card, one of the 30 filling-pieces being removed to provide a coin-receiving space, and a coin placed in said space. Figs. 5, 6 and 7 are modifications to be referred to.

α represents a card, which may be of any 35 suitable shape, size and material, but is usually made of cardboard. It may be arranged in a holder α' , see Fig. 1. Said holder, as here shown, consists of a sheet of paper folded over one edge of the card and 40 attached thereto as at α^2 , thence extended over the back of the card as at α^3 and thence adapted to be extended over the front of the card as at α^4 , and attached at its end to the folded-over portion α^2 ; it having a line 45 of adhesive substance at the end for this purpose. It may also have lines of adhesive substance at the sides and elsewhere.

As here shown the card is arranged to provide for mailing a large number of 50 coins, but so far as my invention is concerned the number of coins provided for is immaterial, except that a certain feature of my invention, as will be hereinafter described, especially provides for more than 55 one.

b represents one of the coin-receiving

spaces normally containing a filling-piece b' , which latter is formed of the material of the cardboard by partially severing the same from the card, in such manner that it 60 is integrally connected therewith at one or more points.

As shown in Figs. 1 to 4, the coin-receiving spaces are made square, and the filling-pieces b' are connected with the card at two 65 opposite corners, as at b^2 , b^3 , or the filling-pieces may be connected with the card at one point only, as b^4 , Fig. 5, which ordinarily will be sufficient for the purpose of holding it securely in place. When it is de- 70 sired to use a space for a coin the filling-piece b' therein is torn out or otherwise removed. The purpose of having the space square, or other than round, is to afford a free entrance for the coin even though mu- 75 tilated or ragged ends are produced when the filling-piece is torn out, or otherwise removed, as shown in Fig. 4, and it will be noted that as the filling-piece is connected at the corners of the space this result may 80 be obtained. In case the space is made round, as shown in Fig. 6, the coin may still be pressed into it, after the filling-piece has been removed, unless very large ragged por- 85 tions are produced by the tearing off opera- 90 tion, although such ragged portions may be trimmed off. Therefore, while in the preferred embodiment of my invention the coin spaces are made square, yet they may be made of any desired shape. In a single 95 card several such coin-receiving spaces may be provided of the same form but of different sizes.

The particular manner here shown of forming the coin-receiving space by first 95 partially severing the card and subsequently tearing out or otherwise removing the filling-pieces admits of the employment of two or more filling-pieces c , c' , c^2 , arranged one within another, see Figs. 2 and 5, to provide 100 coin-receiving spaces of different sizes by removing the innermost filling-piece or both the innermost and the surrounding filling-piece, and so on according to the number of surrounding filling-pieces employed. As 105 here shown such a coin space is provided with three filling-spaces, arranged one within another, and all integrally connected with the card at the corners, or elsewhere, said filling-pieces being represented at c , c' 110 and c^2 . Upon removing the filling-pieces c , a space is provided large enough for a dime,

and upon removing the filling-pieces c and c' , a space is provided large enough for a 25-cent piece, and upon removing all three filling-pieces a space is provided large enough for a 50-cent piece.

I claim:

1. A coin-mailing card having a coin-receiving space with a part thereof extended outwardly beyond the circular contour of the coin, said space being normally filled with a filling-piece which is integrally connected with the card at said outward extension, substantially as described.
2. A coin-mailing card having a coin-re-

ceiving space made square and normally filled with a filling-piece which is integrally connected with the card at one or more corners and is elsewhere separated from the card by a complete line of severance, substantially as described.

20

In testimony whereof, I have signed my name to this specification, in the presence of two subscribing witnesses.

GEORGE A. LOGAN.
